ATTORNEY

UNITED STATES PATENT OFFICE

EDWIN I. THOMPSON, OF FORT WORTH, TEXAS

FOLDING SEAT FOR STADIUMS AND THE LIKE

Application filed October 27, 1930. Serial No. 491,423.

My invention relates to seats and more particularly folding seats; and the object is to provide simple foldable seats which are simple in construction and easily portable and which are strong and durable and constructed of a minimum number of parts and which comfortable seats are for use in stadiums, bleachers, and similar places of public amusement and other public gatherings.

Other objects and advantages will be fully explained in the following description and the invention will be more particularly pointed out in the claim.

Reference is had to the accompanying drawings which form a part of this application.

Fig. 1 is a perspective view of the seat in unfolded condition.

Fig. 2 is a side elevation of the same.

Fig. 3 shows the folded seat.

Fig. 4 illustrates a slight variation.

Similar characters of reference are used to indicate the same parts throughout the several views.

The improved seat has a seat member which has two parallel arms 1 and 2 on the sides and a front bar 3. The arms 1 and 2 and the bar 3 are all made, preferably of a single piece of bendable metal. The metal is bent at the ends to form hooks 4 for engaging the edge of the usual stadium seat, as shown in Fig. 2. The two parts of the bar are then extended horizontally backwardly to form the arms 1 and 2. At the rear ends the

arms have hooks or eyes 5 formed thereon by bending the metal first upwardly and then bending to form the eyes 5 for engaging the members which form the back frame of the seat. A similar piece of metal is used to form the top frame member 6 and the side frame members 7 and 8. The lower ends of the side frame members 7 and 8 are extended to form combined hooks and braces for engaging the eyes 5 and the short upright

shanks 9. The hooks 10 for engaging the eyes 5 are first formed and then the metal bar or rod is further extended to form the braces 11 for engaging the standards 9.

A cloth or cushion 12 is attached to the arms 1 and 2 for a seating member. A cloth

or cushion 13 is attached to the side members 7 and 8 to complete the back of the chair. This seat is made for engaging the board 14 which forms the usual seat of a stadium or bleacher.

In some stadiums the seats are made of cement or concrete. For such structures, the bar 3 is formed on the vertical members 4 and extended across the front as before for engaging the structure 15 without hooking thereunder. The eyes 5 are formed somewhat differently from the eyes of the previous views. The arms 1 and 2 are then extended to form braces 16 to rest on the structure 15. Straps 17 may be attached to the seat for convenience in carrying the seat.

What I claim, is,—

A foldable seat comprising a front bar and side arms and hooks formed at the junction of said bar and arms and spacing said bar from said arms and positioning said bar below said arms, said arms terminating at the rear ends with upstanding standards and eyes formed on said standards, and a back member having top bar and integral arms extending downwardly and terminating with hooks engaging said eyes and the beaks of said hooks engaging said standards for bracing said back member in operative position.

In testimony whereof, I set my hand this 25th day of October, 1930.

EDWIN I. THOMPSON.
